UNITED STATES PATENT OFFICE.

CURT F. ZIMANSKY, OF SAN FRANCISCO, CALIFORNIA, ASSIGNOR TO G. W. PRICE
PUMP AND ENGINE COMPANY, OF SAN FRANCISCO, CALIFORNIA.

PUMP-SHAFT-CENTERING DEVICE.

Application filed May 21, 1921. Serial No. 471,460.

To all whom it may concern:

Be it known that I, CURT F. ZIMANSKY, a citizen of the United States, residing in the city and county of San Francisco, and 5 State of California, have invented a new and useful Improvement in a Pump-Shaft-Centering Device, of which the following is a specification.

My invention relates to improvements in 10 shaft centering devices for deep well pumps of the rotary type wherein a bearing operates in conjunction with the discharge casing to center a pump shaft and casing therefor, and to permit longitudinal movement 15 of said shaft and casing, due to expansion caused by changes in temperature and other causes, within said discharge casing.

The present state of the art discloses deep 20 well pumps wherein a discharge casing has mounted therein and concentrically therewith, a pump shaft and a shaft casing surrounding said shaft. It is essential, owing to the depth of such wells, to provide the discharge and shaft casings as well as the 25 pump shaft, in sections, in order that the mechanism may be properly aligned and assembled.

The depth and consequent length of the 30 casing under ordinary circumstances permits a whipping of the shaft and casing therefor within the well due to the rotation of the shaft. Also the heat created by rotation of the comparatively small diameter shaft and shaft casing creates a difference in temperature between said shaft 35 and casing, owing partly to its greater coefficient of attenuation, and the larger diameter discharge casing, which latter is cooled by the water being discharged there- 40 through, which difference in temperature causes an unequal expansion for which compensation must be made.

The object of the present invention is to 45 provide an improved bearing arranged to not only center the shaft and shaft casing in the discharge casing to prevent lateral movement of said shaft and casing but to also permit a longitudinal movement of one part to the other, such longitudinal movement being created or caused by such difference in temperature and other causes, such as uneven stresses and strains in the several parts.

I accomplish this and other objects by 50 means of the improved device disclosed in

the drawings forming a part of the present specifications wherein like characters are used to designate similar parts throughout the said specifications and drawings, and in which:

Figs. 1 and 1^a are broken vertical sectional views of a deep well pump disclosing the application of the improved device thereto;

Fig. 2 is an enlarged broken view of a 65 portion of a well in vertical section disclosing the device more in detail; and

Fig. 3 is a transverse sectional view taken on line 3—3 of Fig. 2 of the drawings in the direction indicated.

Referring to the drawings the numeral 1 is used to designate a well casing within which is suspended a suitable pump 2 at the lower end of a discharge casing 3. The discharge casing 3 comprises sections connected in spaced relation by means of suitable pipe flanges 4 having registering recesses to provide an annular channel 6 between the adjacent ends of adjacent sections of said casing 3.

Slidably mounted within each annular channel 6 is an annulus or rim 7 of a spider 8 having central hub or bearing portions 9 arranged to rotatably engage and center within the discharge casing 3 a sectional pump shaft 11 connected at its lower end to the pump 2 and provided at its upper end with a suitable pulley 12 by means of which said shaft 11 may be rotated to operate the pump 2 at the lower end thereof.

A discharge head 14 is mounted at the upper ends of the well and discharge casings 1 and 3 respectively, and is provided with a discharge outlet 16.

The hub portion or bearing 9 of the spider 8 is provided with annular shoulders 17 arranged concentric with the bore of said bearing and arranged to rigidly engage the adjacent ends of the adjacent sections of a shaft casing 18 to center said casing and prevent lateral movement relatively to the discharge casing 3.

In operation the friction of the shaft 11 in the bearings 9 of the spider 8 will tend to produce heat and thereby cause expansion of the shaft 11 and the shaft casing 18. It is also obvious that in pumps of this type there is a longitudinal movement of the shaft relatively to the discharge casing during the operation and variation of loads on

the pump runners, not shown, which are secured to said shaft 11.

Furthermore, in assembling the various sections of the shaft, shaft casing and discharge casing, there is bound to be a difference in the length of the various sections which, when multiplied by the number of sections employed, is bound to cause a longitudinal shifting of the shaft and casing 10 therefor relatively to the discharge casing.

As the spider 8 slidably engages the shaft 11 and the discharge casing 3 it is evident that longitudinal movement of any one of the several parts relatively to the others may 15 be readily accomplished by my improved device without causing undue stresses and strains in some of the parts, at the same time centering said several parts and preventing lateral movement thereof, relatively 20 to each other.

Having thus described my invention, what I claim as new and desire to secure by Letters Patent is:

1. The combination with a pump shaft 25 and casing therefor and a discharge casing, of a bearing rotatably engaging the shaft and rigidly engaging the shaft casing and slidably engaging the discharge casing to permit longitudinal movement of said shaft 30 casing relatively to the discharge casing.

2. The combination with a discharge casing and a pump shaft and pump shaft casing mounted therein, of an annulus slidably mounted within said discharge casing and 35 having a bearing formed integral therewith and arranged to rotatably engage the shaft and rigidly engage the shaft casing to center said shaft and to permit longitudinal movement of said shaft casing relatively to the 40 discharge casing.

3. The combination with a discharge casing and a pump shaft and pump shaft casing mounted therein, of a bearing arranged to rotatably engage the shaft to center the 45 same within said discharge casing and hav-

ing concentric shoulders formed on each end of said bearing to rigidly engage and center the shaft casing, said bearing being slidably mounted within the discharge casing to permit longitudinal movement of said bearings and shaft casing relatively to the discharge casing. 50

4. The combination with a discharge casing arranged in sections and a pump shaft and pump shaft casing mounted therein, of flanges connecting the sections in spaced relation to form annular channels between the ends of said sections; and a spider slidably mounted within each annular channel and rotatably engaging the shaft and rigidly engaging the shaft casing to permit longitudinal movement thereof relatively to the discharge casing. 55

5. The combination with a discharge casing of a well, arranged in sections and a pump shaft and shaft casing mounted therein, of flanges connecting said sections in spaced relation to form annular channels between the ends of said sections; bearing 60 slidably mounted within said channels and arranged to center the pump shaft and casing therefor within said discharge casing and to permit longitudinal movement of said shaft and shaft casing within said discharge casing. 65

6. The combination with a discharge casing of a well arranged in sections and a pump shaft and shaft casing also in sections, of flanges connecting said discharge casing sections in spaced relation; and a bearing mounted between the ends of the shaft casing sections and rotatably engaging the shaft and slidably engaging said flanges to permit longitudinal movement of the pump shaft and sections of the shaft casing relatively to the discharge casing. 70 80

In witness whereof I hereunto set my signature.

CURT F. ZIMANSKY.
